UNITED STATES PATENT OFFICE.

FRANK E. CLARK, OF EAST HAMPTON, CONNECTICUT, ASSIGNOR TO
NORMAN N. HILL, OF EAST HAMPTON, CONNECTICUT.

DESIGN FOR AN ACTION-WHEEL FOR TOY BELLS.

SPECIFICATION forming part of Design No. 35,331, dated November 26, 1901.

Application filed October 10, 1901. Serial No. 78,275. Term of patent 7 years.

To all whom it may concern:

Be it known that I, FRANK E. CLARK, of
East Hampton, in the county of Middlesex and
State of Connecticut, have invented and pro-
duced a new and useful Design for an Action-
Wheel for Toy Bells; and I do hereby declare
the following, when taken in connection with
the accompanying drawings and the letters of
reference marked thereon, to be a full, clear,
and exact description of the same, and which
said drawings constitute part of this specifi-
cation, and represent, in—

Figure 1, a face or plan view of a wheel em-
bodying my design; Fig. 2, a sectional view
of the same.

This invention relates to a design for an
action-wheel for toy bells; and the design con-
sists in a wheel having a rim A, spokes B,
and a star-shaped hub C, the hub being off-

set on one side from the plane of the rim and 20
spokes, the number of points of the star cor-
responding to the number of spokes and one
of said points extending onto each of the said
spokes, all as shown in the accompanying
illustrations.

Having fully described my invention, what 25
I claim, and desire to secure by Letters Pat-
ent, is—

The design for an action-wheel for toy bells,
as herein shown and described.

In testimony whereof I have signed this
specification in the presence of two subscrib-
ing witnesses.

FRANK E. CLARK.
